Primary Examiner — Sandra L Morris

(57) **CLAIM**

The ornamental design for a leaf-style packaging container, as shown and described.

DESCRIPTION

FIG. 1 is a front perspective view of a leaf-style packaging container, showing the new design;

FIG. 2 is a front view thereof;

FIG. 3 is a rear view thereof;

FIG. 4 is a side view thereof;

FIG. 5 is the opposite side view thereof;

FIG. 6 is a top plan view thereof; and,

FIG. 7 is a bottom view thereof.

In all figures, the broken lines showing the environmental subject matter are included for illustrative purposes and form no part of the claimed design.

1 Claim, 7 Drawing Sheets
